UNITED STATES PATENT OFFICE.

GEORGE W. BUNNELL, OF MERIDEN, CONNECTICUT, ASSIGNOR TO
C. ROGERS & BROS., OF SAME PLACE.

DESIGN FOR COFFIN-HANDLE TIP.

Specification forming part of Design No. 7,630, dated August 11, 1874; application filed July 13, 1874.
[Term of Patent 7 years.]

To all whom it may concern:

Be it known that I, GEORGE W. BUNNELL, of Meriden, in the county of New Haven and State of Connecticut, have invented a new Design for Coffin-Handle Tip; and I do hereby declare the following, when taken in connection with the accompanying drawings and the letters of reference marked thereon, to be a full, clear, and exact description of the same, and which said drawings constitute part of this specification, and represent a side view.

This invention relates to a design for the tips or ends of the bar in coffin-handles; and it consists in the peculiar configuration of the tip, as shown in the accompanying illustration, and which I will proceed to describe.

The base is of ogee form, to a bead, *a*. From this bead the tip contracts in ogee form to a second bead, *b*; thence terminating in a conoidal form, as shown.

I claim—

The design for tip for coffin-handles, consisting of the base, two beads, *a* *b*, and intermediate section and termination, as shown in the accompanying illustration.

GEO. W. BUNNELL.
